[57] CLAIM

The ornamental design for liquid dispenser, as shown.

DESCRIPTION

FIG. 1 is a front perspective view of the liquid dispenser of the present invention;

FIG. 2 is a front elevational view of the dispenser;

FIG. 3 is a back elevational view of the dispenser;
FIG. 4 is a side elevational view of dispenser, the opposite side being identical;

FIG. 5 is a top plan view of the dispenser; and,
FIG. 6 is a bottom plan view of the dispenser.

The broken-line disclosure in the views is for illustrative purposes only and forms no part of the claimed design.
